UNITED STATES PATENT OFFICE.

WALLACE WARREN, OF CHICAGO, ILLINOIS, ASSIGNOR OF ONE-HALF TO
FRANK C. TAYLOR, OF SAME PLACE.

BRAN-FLOURING MACHINE.

SPECIFICATION forming part of Letters Patent No. 254,784, dated March 7, 1882.

Application filed August 15, 1881. (No model.)

To all whom it may concern:

Be it known that I, WALLACE WARREN, of Chicago, State of Illinois, have invented certain new and useful Improvements in Bran-
5 Flouring Machines; and I do hereby declare that the following is a full, clear, and exact description thereof, reference being had to the accompanying drawings, and to the letters of reference marked thereon, which form a part
10 of this specification.

This invention relates to apparatus for com-
minuting bran, and is the same as that illus-
trated in another patent to me of even date
herewith, wherein I have described a new
15 method and product in the manufacture of
whole-wheat flour, or flour made from the
inner grain substance together with portions of
the bran. A distinctive feature of such flour
is that the bran is reduced by itself or sepa-
20 rately from the inner substance of the grain to
a degree of fineness substantially equal to that
of the starchy portions, and is thereafter mingled
with such starchy portions to form the
improved product mentioned. The reduction
25 of the bran to a suitable degree of fineness is
difficult or impossible by ordinary grinding-ma-
chines, the object of such machines being gen-
erally to effect only the reduction of the inner
portion of the grain and to avoid the reduc-
30 tion of the bran. The purpose of this inven-
tion is to provide a suitable means for the re-
duction of the bran to the degree of fineness
required.

Said invention consists in the several de-
35 vices and combination of devices hereinafter
described, and pointed out in the claims, and
is herein illustrated in a machine comprising
a circular shell having its inner periphery cov-
ered by a sharply-rough surface, and a winged
40 disk mounted to rotate rapidly within the
shell, whereby the bran fed into the shell near
its center is rapidly swept about and against
the sharp serrations mentioned, which cut the
bran into fine particles. A marginal opening
45 in each side of the shell allows the bran-flour
or comminuted bran to escape by being blown
out by the action of the wings of the disk when
sufficiently reduced.

In the drawings, Figure 1 is a central sec-

tion of the machine, taken at right angles to 50
the disk-axis. Fig. 2 is a central vertical sec-
tion through the disk-axis. Fig. 3 is a side
elevation of the machine and a vertical sec-
tion of the housing, into which the machine
discharges; and Figs. 4, 5, and 6 are details. 55

A is the circular peripheral wall of the shell,
and consists of two semicircular cast-iron bodies
about eight inches wide, each provided with
a foot-piece, A', by which the parts are sup-
ported on the bed-plate B to form, when 60
brought together, a circular band of about five
feet in diameter. These parts are held united
by the bolts which confine the same to the
bed-plate B by flanges and bolts at the top,
and by the circular side plates, A², which are 65
secured to the edges of the band A by bolts a.
Said side plates are made in two parts, and are
flanged and joined in the same plane with the
band A.

C are a number of narrow steel plates, 70
which form the inner peripheral surface of the
shell, and which are held in place against the
peripheral band A by means of the annular
recesses a² in the side plates, A², in which said
narrow plates C rest. 75

D is a smooth steel disk mounted upon the
central shaft, E, which is supported in the ex-
ternal bearing-blocks, H H, upon both sides
of the shell, and is provided with the pulley
P. Said bearing-blocks rest broadly on the 80
same strong bed-plate B, so as to support the
disk D centrally and accurately parallel with
the interior sides of the shell A A². The disk
D is secured to the shaft E by means of the
right and left threaded nuts F F, one on each 85
side of the disk, between which nuts and the
disk are inserted smaller disks or plates D',
the larger of which are preferably riveted
firmly to the disk D. Said disk is set and
thus secured with the utmost accuracy at right 90
angles to the shaft E, so as to run perfectly
true and noiselessly. The disk D is in diam-
eter about one and one half inch less than that
of the shell interior after the plates C C are in
place, so that the edge of said disk runs at all 95
points at about three-fourths of an inch from
said plates C. The outer margin of said disk
is provided with a series of wings, I I, one of

which is shown detached in Fig. 5, wherein it will be seen a slot, *i*, is provided in the wing-plate, by which said plate embraces the edge of the disk *D*. Said wing-plate is also bent to 5 nearly a right angle at the inner end of the slot *i*, giving the flange *I*², which, when the wing is applied to the disk, rests against the edge of the latter.

To fasten the wing-plates firmly to the disk 10 *D* angle-irons *I'* are riveted on opposite sides of said disk, as indicated in Figs. 1 and 2. To these angle-irons the wing-plates are also riveted, as also shown by said Figs. 1 and 2. The disk *D* is about one-fourth of an inch in thickness, and the wings *I* are about one-eighth of 15 an inch in thickness. The wing-flanges *I*² therefore run about five-eighths of an inch from the surfaces of the plates *C C*. At the sides they run in as closely to the shell-walls *A*² as practicable. These dimensions may be varied. The inner faces of the steel plates *C C* 20 are sharply serrated, like a single-cut file, the serrations in alternate plates running preferably in oppositely-oblique directions, as shown 25 in Fig. 2.

Feed-pipes *R R* enter the shell at opposite points in the side plates, *A*², near the center of the machine. Discharge-openings *J* are also provided through the side plates, *A*², opposite each other and at the inner periphery of the shell, each of which openings is provided with the gate *L*, running in guides *j*, and provided with the slots *l*, not narrower than the openings *J*. By means of the sliding 35 gate *L*, having the slot *l*, the opening *J* may be narrowed and its outer margin at the same time moved toward the center of the machine. For the purpose of moving and holding the gate *L* the latter has the threaded lug *l'*, and 40 the plate *A*² has the opposite lug, *l*², to which lugs the adjusting-screw *L'* is fitted, as shown in Fig. 3. The said openings *J* are located preferably on a horizontal line with the shaft *E*, as clearly shown, and a portion of the shell 45 containing said openings is housed within the chamber *M*. The bottom walls, *n*, of said chamber are inclined, giving the hopper *N*, in the bottom of which is located the conveyer *N'*. The chamber *M* is divided by a dust-cloth, *O*, and above or outside said dust-cloth 50 the said chamber has an outlet for the escape of air.

In the operation of this machine the disk *D* is revolved at a high velocity. The bran is 55 fed to the interior of the shell through the pipes *R*, and is at once carried outward to the periphery of the shell and rapidly swept about therein against the sharply-serrated faces of the steel plates *C*. In this movement the bran 60 is rapidly and finely comminuted, and when reduced to the condition of fine flour escapes by the openings *J* into the chamber *M*, where

it is collected, and whence it is removed by the conveyer *N'*. By drawing the gate *L* inward, and thereby increasing the distance of 65 the openings *J* from the inner periphery of the shell, the bran may be longer retained therein and more finely reduced.

The dust-cloth or diaphragm *O* may represent a series of arresters, by which the entire 70 bran product will be recovered from the air-current. Such devices for arresting the bran-flour may be located in other positions than that shown, and they may be provided with any suitable means for detaching and collecting the bran-flour therefrom. Plainly, in the rapid rotation of the disk *D* a strong current of air will be induced downward through the pipes *R* and outward through the openings *J*. It is found that the action of the air operates 75 to abstract moisture from the bran developed in its reduction, and thereby contributes to the keeping qualities of ultimate product in which it is combined.

I have as a substitute for the steel file-cut 80 plates *C C* used blocks of burr-stone with fair results; but the cut steel plates are preferable.

I claim as my invention—

1. In a bran-flouring machine, the combination, as shown, of the cylindric shell and winged 90 disk, said shell having its inner periphery minutely and sharply rough, as described, and having a suitable inlet and a lateral adjustable outlet located near but slightly inward from the periphery, whereby the bran may be 95 swept about against the rough face of the shell until suitably reduced and then discharged, substantially as described.

2. In combination with the shell having the lateral marginal opening *J*, the slide *L*, having the slot *l* arranged with the opening *J*, so as to vary the distance of the discharging- 100 orifice from the periphery of the shell, substantially as described, and for the purposes set forth.

3. In the bran-reducing machine described, the disk *D*, provided with the wings *I*, having the flanges *I*² turned backward and supported from the disk at the outer margin of the wings, substantially as described.

4. In the bran-reducing machine described, the disk *D*, provided with opposite wings, *I*, each pair consisting of a single plate having a slot, *i*, and bent at the extremity of the slot, as shown and described, and for the purposes 115 set forth.

In testimony that I claim the foregoing as my invention I affix my signature in presence of two witnesses.

WALLACE WARREN.
